(57) CLAIM

(21) Appl. No.: **29/137,397**

The ornamental design for a staggered look shake siding panel, as shown and described.

(22) Filed: **Feb. 20, 2001**

DESCRIPTION

(63) Continuation of application No. 09/735,681, filed on Dec. 13, 2000, which is a continuation-in-part of application No. 09/190,038, filed on Nov. 12, 1998.

FIG. 1 is a broken front perspective view of a staggered look shake siding panel showing our new design and having adjacent shingle impressions;

(51) LOC (7) Cl. **25-01**
(52) U.S. Cl. **D25/143**
(58) Field of Search **D25/139, 143; 52/314, 555, 557, 560**

FIG. 2 is a front elevational view of the staggered look shake siding panel;

FIG. 3 is a rear elevational view of the staggered look shake siding panel;

FIG. 4 is a cross-sectional, side elevational view of the staggered look shake siding panel taken along lines 4—4 of FIG. 2; and,

FIG. 5 is a cross-sectional, side elevational view of the staggered look shake siding panel taken along lines 5—5 of FIG. 2.
